ORNAMENTAL BOW MAKING APPARATUS
Clarence T. Bickner, P.O. Box 957,
El Sobrante, Calif. 94803
Filed Sept. 16, 1966, Ser. No. 579,889
4 Claims. (Cl. 248—349)

ABSTRACT OF THE DISCLOSURE

The invention relates to a rotary support for a device used in making ornamental bows from ribbon or tape. The rotary support has upper and lower discs which rotate relatively to one another, the upper disc being coated with a pressure sensitive adhesive to cause it to adhere to the underside of a bow maker, the lower disc being also coated with a pressure sensitive adhesive to cause it to adhere to a table top or the like. Each coated surface is protected, until the time of use, by a masking material which can be peeled off.

This invention relates to an ornamental bow making apparatus and more particularly to a rotatable supporting device for rotatably supporting one member with respect to a second member, which device may be employed in a bow making apparatus.

In certain types of apparatus for making ornamental bows a rotatable disc is employed having means at the center thereof for detachably holding a bow pin with its spike projecting upwardly. In the formation of an ornamental bow an end of a ribbon is impaled on the bow pin, and the ribbon is formed with the desired number of loops. During the formation of the loops of the bow the disc is rotated. Such bow making apparatus is shown in my copending patent application entitled, "Apparatus and Method for Making Ornamental Bows," filed Oct. 21, 1965, Ser. No. 505,589. The rotatable fastening device of the present invention is particularly useful in the construction of a bow making apparatus. However, numerous other uses for the rotatable fastening device will be readily apparent and it will be understood that the device is not limited to any particular use.

An object of this invention is the provision of an improved rotatable coupling or supporting device which is easily and economically produced and is of rugged design.

An object of this invention is the provision of an ornamental bow making apparatus having a novel rotatable supporting device by means of which the apparatus may be attached to a plane surface.

An object of this invention is the provision of a rotatable attaching device having substantially plane parallel surfaces for readily attaching the same to members to be relatively rotatably supported.

These and other objects and advantages of the invention are achieved by use of a first pair of discs each of which discs has a central aperture through which a connecting member such as a grommet or tubular rivet extends for rotatably coupling the discs. A second pair of discs, each of which has a central aperture of sufficient size to accommodate the grommet or rivet heads, is fastened to the outer sides of the first pair of discs. The discs of the second pair are of greater thickness than the height of the grommet or rivet heads whereby the heads are entirely contained within the apertures therein.

In the drawings wherein like reference characters refer to the same parts in the several views:

FIGURE 1 is an exploded perspective view showing the novel coupling device of this invention.

FIGURE 2 is a cross sectional view taken on line 2—2 of FIGURE 1.

2

FIGURE 3 is a top plan view of a bow making apparatus employing the rotatable supporting device of this invention, and

FIGURE 4 is a side elevational view of the bow making apparatus shown in FIGURE 3.

Referring now to FIGURES 1 and 2 of the drawings, the rotatable coupling or supporting device, designated generally by the reference character 10, comprises a pair of plates or discs 12 of identical construction. The illustrated plates are of circular shape, although other shapes such as square, rectangular, and the like may be employed.

The plates 12 are provided with central apertures 14 through which a connecting member such as a grommet or tubular rivet 16 extends for rotatably fastening the plates together. The apertures 14 have reduced diameter portions 14a at the inner faces of the plates to accommodate the rivet shank 16a, and enlarger diameter portions 14b at the outer faces to accommodate the rivet heads 16b. In the upset condition of the rivet as illustrated in FIGURE 2, the length and diameter of the rivet shank are such that the plates are free to rotate on the member 16. It will be noted, as seen in FIGURE 2, that the rivet heads 16b are recessed in the plates and do not protrude beyond the outer surfaces of the plates. As a result, the coupling may be readily secured to flat surfaces in a manner described below.

To facilitate securing the plates 12 to the members to be relatively rotatably fastened together, a layer of pressure sensitive adhesive 20 is provided on the outer face of the plates. The adhesive layers preferably are covered with peelable protective sheets 22 of paper, or the like, which are removed when the device is to be used.

The plates 12 may be made of any suitable material such as metal, plastic, cardboard, or the like, and by any suitable means. In the illustrated construction, each plate is shown comprising a pair of disc or plate members 12a and 12b which are secured together as by pressure sensitive adhesive 24. The members 12a are formed with the apertures 14a and the members 12b are formed with the larger apertures 14b. The members 12a and 12b are secured together with the apertures 14a and 14b in axial alignment to form the apertures 14 shown in FIGURE 2.

The coupling is easily and economically constructed. The disc or plate members 12a are readily die cut from uncoated sheets, and readily fastened together by the connector 16. The disc or plate members 12b may be cut from sheets with pressure sensitive adhesive on both sides thereof, and with a peelable protective layer on at least one of the adhesive layers. The disc members 12b may be secured to the members 12a either before or after the members 12a are coupled by the rivet 16.

Although the layers 20 and 24 are described as pressure sensitive adhesive, other suitable adhesives, cement, or the like, may be employed. Further, the tubular rivet or grommet 16 may be replaced with some other suitable connecting means such as a solid rivet or the like.

The device 10 is particularly useful in the construction of bow making apparatus such as illustrated in FIGURES 3 and 4 of the drawings, to which reference is now made. The illustrated bow making apparatus comprises a flat plate 40 of circular shape, although other shapes may be employed. A pattern of concentric circles and radial lines may be printed or otherwise suitably formed on plate 40 as shown in FIGURE 3, which circles and lines serve to guide the operator in the formation of a bow in the manner described in my above-mentioned copending patent application. A bow pin holder 46 is provided at the center of the base, for support of a bow pin not shown. The holder 46 is also of a type shown in said copending patent application, and may simply comprise a disc 48 of plastic material affixed along its outer edge at 50 to the

base 40, for example, by means of adhesive, which disc 48 is formed with a radial slot 52 to receive a bow pin.

The rotatable supporting device 10 of this invention is secured to the opposite or bottom surface of the base 40 in axial alignment with the bow pin holder 46 for rotatable support thereof. This simply is done by removing the protective layer 22 from one of the plates 12 and then pressing the plate against the base 40. The protective layer 22 on the other plate is then removed for attachment of the device to any desired supporting surface such as a desk, table, counter top, or the like, not shown. Obviously, the device may be secured to other means such as the side of a ribbon roll, to the top of a box or container for bow pins, or the like. The method of using the rotatable bow making apparatus 40 in the formation of an ornamental bow is described in detail in my said pending patent application and such method need not be repeated here.

The invention having been described in detail in accordance with the requirements of the Patent Statutes various changes and modifications may suggest themselves to those skilled in this art and it is intended that such changes and modifications shall fall within the spirit and scope of the invention as defined in the appended claims.

I claim:

1. A rotary support for a bow making device comprising adjacent and concentric first and second discs; connector means connecting said discs to prevent relative axial and radial displacement thereof but permitting rotation of each of the discs in relation to the other disc about their common axis, said connector means being recessed

5
10
15

in relation to the exposed surfaces of said discs; a layer of pressure sensitive adhesive on the exposed surface of each disc; and a layer of masking material adhering to each layer of pressure sensitive adhesive, said layers of masking material being removable by peeling to expose the underlying layers of pressure sensitive adhesive.

2. The rotary support of claim 1 wherein each disc is formed with a stepped, central recess having a wider outer portion and a narrower inner portion, said connector means extending through said inner portions and having ends of greater diameter than said inner portions, such ends being lodged in and rotatable in said outer portions.

3. The rotary support of claim 2 wherein each disc is formed of an inner disc member and an outer disc member, said inner and outer disc members being separately punched to form said narrower portions in the inner disc members and said wider portions in the outer disc members.

4. The rotary disc of claim 3 wherein the inner disc members are adhesively bonded to the respective outer disc members.
